CONTAINER CAP-SUPPORTING ATTACHMENT

Joseph R. Woody, Stuarts Draft, Va.

Application May 27, 1949, Serial No. 95,851

4 Claims. (Cl. 220—30.6)

1

This invention relates to a supporting device for container caps, and more particularly to a spring-actuated device for a container cap which is operable to move the cap into closed and open positions relative to the container.

The primary object of the invention is to provide a cap-supporting device which is easily secured to the conventional container employing a removable cap, such as a tooth powder or shaving cream container.

Another object of this invention is to provide a cap-supporting device which is secured by a suitable means to the discharge orifice of a conventional container and which is operable to move the container cap into open and closed positions relative to the discharge orifice.

A further object of the invention is to provide a cap-supporting device which can be easily adapted to the discharge nozzles of containers.

Other and further objects and advantages will become apparent from the following description of the drawing, wherein:

Figure 1 is an elevational view of the device forming this invention mounted on the discharge nozzle of a conventional container with the cap of the container bell in a closed position;

Figure 2 is a similar view showing the cap of the container in threaded engagement with the nozzle of the container;

Figure 3 is a top plan view of the device shown in Figure 1;

Figure 4 is a plan view in partial cross-section taken along the line 4—4 of Figure 5;

Figure 5 is an elevational view of the device mounted on a container with the cap held in an open position and with a portion of the device shown in cross-section to show the method employed to secure the device to the nozzle of the container;

Figure 6 is a perspective view of the device mounted on a conventional container and with the container cap in a closed position;

Figure 7 is an elevational view of another form of the device mounted on a conventional container with the container cap in a closed position;

Figure 8 is a view similar to Figure 7 but with the container cap in an open position;

Figure 9 is a view in cross-section of the modified form of Figure 7 taken along the line 9—9 of Figure 11;

Figure 10 is a plan view of the cap-supporting member of the modified form shown in Figure 7;

Figure 11 is a plan view of the nozzle-engaging member of the modified form shown in Figure 7;

2

Figure 12 is a side elevational view in partial cross-section of the cap-supporting member taken along the line 12—12 of Figure 10;

Figure 13 is an elevational view of a further form of the device mounted on a conventional container with the container cap in a closed position;

Figure 14 is a plan view in partial cross-section taken along the line 14—14 of Figure 13.

10 In the drawings, wherein like numerals refer to identical parts, the device forming this invention, as seen in Figures 1 through 6 and most clearly in Figure 6, comprises a nozzle-engaging member 15 and a cap-supporting member 16 which is operatively connected to the member 15. The nozzle-engaging member is designed to be mounted on the discharge nozzle 17 of a conventional commercial container 18, such as might contain tooth paste, shaving cream or the like.

15 20 The cap-supporting member 16 is likewise designed to support the cap 19 provided for the container 18.

The nozzle-engaging member 15 comprises a centrally-apertured skirt 20, which is preferably 25 of a frusto-conical configuration to embrace the tapered neck 21 of the container 18. The apertured skirt 20 is provided with a thread-engaging edge 22 adjacent its inner periphery to engage the threads 23 of the nozzle 17, as shown in Figure 5. Depending from the apertured skirt 20 and connected thereto is a guide plate 24 extending radially from the nozzle, the guide plate being formed to conform to the adjacent surface of the tapered neck 21. The guide plate 24 is integrally connected to a cantilever or semi-elliptical spring arm 25 which extends in approximate parallelism with the longitudinal axis of the nozzle. The free end of the arm 25 is notched, as at 26, and is laterally spaced from the open end of the nozzle 17. The arm 25 is provided with a longitudinal slot 27 for a purpose to be discussed later.

40 The cap-supporting member 16 is of right-angled construction, the legs being pivotally connected at their juncture point 27' to the free end of the spring arm 25. One leg 28 of the member 16 is bifurcated to receive the cap 19. The leg 28 is peeled at its center from a point adjacent its bifurcation to form a thumb lever 29, which is bent back over the juncture 27' of the leg 28 with the other leg 30, the thumb lever 29 being movable through the longitudinal slot 27 of the arm 25. The leg 30 is provided with opposed slots 31 adjacent the juncture 27' of the member 16 to permit the leg 30 to fit within

the notched end 26 of the spring arm 25. Thus, the member 16 is pivotally connected to the free end of the spring arm 25. The free end of the leg 30 is disposed in slidable contact with the guide plate 24, the movement of the free end being limited by a stop 32 in the guide plate and the base of the spring arm 25.

The device may be used with a conventional container, as 18, the centrally-apertured skirt 20 being positioned on the discharge nozzle 17, and then being rotated thereon, so that the thread-engaging edge 22 of the skirt 20 tightly engages the threads 23 of the nozzle. The bifurcated leg 28 of the cap-receiving member 16 is spread to accommodate the cap 19. When it is desired to open the container, the thumb lever 29 is depressed, and the free end of the leg 30 will slide along the guide plate 24 to its limited position adjacent the stop 32, as shown clearly in Figure 5. In such a position, the spring arm 25 will be forced into a resistive or flexed condition, whereby the free end of the spring arm 25 compresses the free end of the leg 30 against the guide plate 24 to thereby retain the cap 19 in an open position relative to the container 18. To close the container 18, the thumb lever 29 is moved in an opposite direction and the operation is reversed, the result being that the cap 19 is forced and held in tight contact with the top of the nozzle 17, as shown in Figure 1. If desired, the cap 19 may be rotated on the nozzle 17 so as to be threadedly engaged with the threads 23 on the nozzle, as shown in Figure 2. This latter operation is feasible, due to the loose mounting of the cap 19 in the bifurcated leg 28 and the fact that the leg 30 is adapted to be flexed longitudinally.

The modification of the device shown in Figures 7 through 12 is essentially the same as the previously-described preferred form. However, the structure of the nozzle-engaging member 15 has been modified, wherein a center portion 33 of the spring arm 25 is peeled back into an overlying relationship with respect to the guide plate 24. The free end of the center portion or retaining spring 33 is inserted within a groove 34 of the nozzle 17, thereby securely holding the nozzle-engaging member 15 in position on the nozzle 17. The free end of the leg 30 is notched, as at 35, Figure 12, to receive the retaining spring 33 therein and to permit the slidable contact of the free end with the guide plate 24. A stop 36 is provided adjacent the free end of the retaining spring 33 to limit the movement of the free end of the leg 30. As is apparent, the apertured member 20 of this form is not provided with a thread-engaging edge as is provided in the previous form of the device, since the retaining spring 33 serves to perform the equivalent function of securing the nozzle-engaging member 15 to the nozzle 17.

The other modified form of the device, as shown in Figures 13 and 14, is similar to the form of Figure 1, with the exception that a second centrally-apertured skirt 37 is disposed in superposed concentric position relative to the first apertured skirt 20 and is integrally connected to the latter. The second apertured skirt 37 is provided with saw teeth 38 adjacent the aperture thereof, which are adapted to cut a groove in the nozzle 17' of a container 18', which represents a conventional commercial container provided with an unthreaded lower portion of its nozzle. A bar 39 is disposed through the apertured skirts 20 and 37 for the purpose of

moving the latter members from a normally eccentric position to a concentric position to permit fastening or positioning the skirts 20 and 37 when so concentrically aligned on the nozzle 17' of the container 18'. By rotation of the container relative to the apertured skirts 20 and 37, the saw teeth 38 cut a groove in the unthreaded lower portion of its nozzle 17'. The teeth 38 are provided with stop flanges 40 to limit the depth of cut, so as to avoid impairing the nozzle 17'.

I claim:

1. The combination with a container having a nozzle at one end and a cap for the nozzle, of a guide plate extended radially from the nozzle; means connecting said plate at one end thereof to the nozzle; a semi-elliptical spring fixed at one end to the other end of the guide plate in approximate parallelism with the longitudinal axis of the nozzle and tensioned at its other end to exert a continuous pressure in the general direction of the opposite end of the container; a cap-supporting member including a pair of perpendicularly related legs fixedly joined at one end thereof and pivotally connected directly to the spring at their juncture point, the cap being separably connected to the other end of one leg, the other end of the second leg sliding longitudinally of the guide plate to opposite extreme positions adjacent the nozzle and spring, respectively, said spring in the respective positions of the second leg biasing said member to nozzle-uncapping and capping positions, respectively; and a thumb lever rigid with the first-named leg and constituting means for swinging said member to each of its respective positions, the second leg being forced against the guide plate by the spring to retain said member in the nozzle-uncapping position thereof.
2. The combination with a container having a threaded nozzle at one end and a cap threadable upon the nozzle, of a guide plate extending radially from the nozzle; a skirt rigid with the guide plate at one end thereof and circumscribed about the nozzle, said skirt having a thread-engaging edge thereon engageable with the threads of the nozzle to connect the guide plate to the nozzle; a semi-elliptical spring fixed at one end to the other end of the guide plate in approximate parallelism with the longitudinal axis of the nozzle and tensioned at its other end to exert a continuous pressure in the general direction of the opposite end of the container; a cap-supporting member including a pair of perpendicularly related legs fixedly joined at one end thereof and pivotally connected directly to the spring at their juncture point, the cap being separably and rotatably connected to the other end of one leg, the other end of the second leg sliding longitudinally of the guide plate to opposite extreme positions adjacent the nozzle and spring, respectively, said spring in the respective positions of the second leg biasing said member to nozzle-uncapping and capping positions, respectively; and a thumb lever rigid with the first-named leg and constituting means for swinging said member to each of its respective positions, the second leg being forced against the guide plate by the spring to retain said member in the nozzle-uncapping position thereof, said second leg being proportioned for longitudinal flexure thereof responsive to threading of the cap onto the nozzle in the nozzle-capping position of said member.
3. The combination with a container having a threaded nozzle at one end and a cap threadable

upon the nozzle, said nozzle having a circumferential groove at the base of the threaded portion thereof, of a guide plate extending radially from the nozzle; a skirt rigid with the guide plate at one end thereof and circumscribed about the nozzle; a retaining spring rigidly connected at one end to the guide plate and having its other end extending into the groove, said retaining spring comprising means cooperating with the skirt to connect the guide plate at one end thereof to the nozzle; a semi-elliptical spring fixed at one end to the other end of the guide plate in approximate parallelism with the longitudinal axis of the nozzle and tensioned at its other end to exert a continuous pressure in the general direction of the opposite end of the container; a cap-supporting member including a pair of perpendicularly related legs fixedly joined at one end thereof and pivotally connected directly to the second-named spring at their juncture point, the cap being separably and rotatably connected to the other end of one leg, the other end of the second leg sliding longitudinally of the guide plate to opposite extreme positions adjacent the nozzle and spring, respectively, said second-named spring in the respective positions of the second leg biasing said member to nozzle-uncapping and capping positions, respectively; and a thumb lever rigid with the first-named leg and constituting means for swinging said member to each of its respective positions, the second leg being forced against the guide plate by the spring to retain said member in the nozzle-uncapping position thereof, said second leg being adapted for longitudinal flexure thereof responsive to threading of the cap onto the nozzle in the nozzle-capping position of the cap-supporting member.

4. The combination with a container having a nozzle at one end a cap for the nozzle, of a guide plate extended radially from the nozzle; a skirt rigid with the guide plate at one end thereof and circumscribed about the nozzle; a second skirt circumscribed about the nozzle and fixedly connected to the first skirt, said second skirt having a series

of teeth engageable in the nozzle for connecting the guide plate to the nozzle; a semi-elliptical spring fixed at one end to the other end of the guide plate in approximate parallelism with the longitudinal axis of the nozzle and tensioned at its other end to exert a continuous pressure in the general direction of the opposite end of the container; a cap-supporting member including a pair of perpendicularly related legs fixedly joined at one end thereof and pivotally connected directly to the spring at their juncture point, the cap being separably connected to the other end of one leg, the other end of the second leg sliding longitudinally of the guide plate to opposite extreme positions adjacent the nozzle and spring, respectively, said spring in the respective positions of the second leg biasing said member to nozzle-uncapping and capping positions, respectively; and a thumb lever rigid with the first-named leg and constituting means for swinging said member to each of its respective positions, the second leg being forced against the guide plate by the spring to retain said member in the nozzle-uncapping position thereof.
